UNITED STATES PATENT OFFICE.

FRANK J. BERG, OF DUBUQUE, IOWA.

AUTOMATIC FIRE-LIGHTER.

SPECIFICATION forming part of Letters Patent No. 386,232, dated July 17, 1888.

Application filed October 19, 1887. Serial No. 252,815. (No model.)

To all whom it may concern:

Be it known that I, FRANK J. BERG, of Dubuque, in the county of Dubuque and State of Iowa, have invented a new and Improved Automatic Fire-Lighter, of which the following is a full, clear, and exact description.

My invention relates to a device for automatically lighting or kindling fires at any predetermined time, and has for its object to provide a simple, inexpensive, and effective device of this character.

The invention consists in certain novel features of construction of the fire-lighter, all as hereinafter described and claimed.

Reference is to be had to the accompanying drawings, forming a part of this specification, in which similar letters of reference indicate corresponding parts in all the figures.

Figure 1 is a side elevation of my improved fire-lighter with the fire grate and kindler indicated in dotted lines. Fig. 2 is a plan view of the fire-lighter, and Fig. 3 is a detail rear sectional view of a portion of the alarm-clock mechanism and the end of the trip arm of the fire-lighter mechanism.

A metal bed-plate, A, from which the fire-lighter mechanism is supported, is provided with a couple of lugs, *a a*, to which is journaled on screw-shafts or gudgeons *b b*, or otherwise, a rock-shaft, B, which carries fixedly a couple of arms, C C, to which are pivotally connected at *c c* the rear end parts of the bifurcated plate or bar D, which at its forward end is provided with an eye or socket, *d*, to receive a match, E, which may fit the eye tightly, but is preferably held in the eye by a hook, F, which is pivoted at *f* to the bar D, and has a bill or point, *f*, which enters the eye *d* at the side of the match and wedges the match securely in the eye.

On the bed-plate A, at its forward end, is held, preferably by long staples or wire clips or clamps *g g*, a piece, G, of sand-paper, on which the ignitable end of the match E rests, and to the forward end of the bed-plate are fixed or held in any suitable manner a couple of wire hooks, H H, on or in which a wad or bunch, I, of paper, shavings, tinder, or other readily-ignitable material, will be held in proximity to the fire-grate J of a stove or fire-place, and so that when the wad I is lighted by the match the fire will be started or lighted in the grate. The

wad and grate are shown in dotted lines in Fig. 1 of the drawings.

To the rock-shaft B is fixed a trip arm, K, which, when the fire-lighter mechanism is set ready for action, catches beneath a latch arm or bar, L, which is fitted to the alarm-clock M and passes through a hole, *m*, in the clock-ease, and is pivoted at *l* to one end of a lever, N, which is pivoted at *n* to the clock-works frame, and at its other end rests against a cam or eccentrically-set disk or wheel, O, which is fixed to the spring-shaft *o* of the alarm mechanism of the clock, and is brought into proper position for action, as shown in Fig. 3 of the drawings, by the winding up of the alarm-spring. When the alarm-hand P is set to any time on the alarm-dial and this time is recorded or indicated by the hands R on the main dial of the clock, the alarm will be tripped and its mechanism will ring the alarm-bell, and as the alarm-spring unwinds and carries the cam O around with it said cam will operate the lever N and draw the bar L inward to release the trip-arm K.

Rubber or other suitable buffers, T, are fixed to the bed-plate A to receive the arms C or bar D when the fire-lighter mechanism is tripped, and thereby prevent noisy contact of the metal parts. The clock M is preferably supported on a depressed portion, A', of the bed-plate A, which part A', in connection with front legs, *a'*, supports the device in proper position on the hearth-plate of a stove, or on the hearth-stone of a fire-place. A spring, S, fixed to the bed-plate A and one of the pivots *c*, or to one of the arms C, tends normally to contract and impart motion to the bar D, for carrying the match across the sand-paper for lighting the match and wad I for kindling the fire.

The operation of the fire-lighter is as follows: After the alarm is set to be rung at the desired time, the bar D will be grasped, preferably by a knob, D', provided on it for the purpose, and its end holding the match E will be lifted from the sand-paper and the bar will be moved over toward the clock M, which motion will swing the rock-arms C of the shaft B over on the bearings *b b*, and also carry the trip-arm K over and cause it to catch beneath the latch-bar L of the clock. The rearward movement of the bar D also puts the spring S in tension,

and when the match E is lowered gently to the sand-paper G, or other roughened face on which it may easily be ignited by friction, the device is ready for action. The weight of the 5 knob D' holds the match to the sand-paper with sufficient force to assure lighting of the match when the device is tripped into action. When the latch-bar L is withdrawn by the clock mechanism from the trip-arm K, the 10 spring S will act instantly to throw the arms C C and the bar D forward and carry the match E over the sand-paper G and light it, and cause the match to light the wad or kindler I, which in turn will light the fire in the grate J. The 15 parts C or D, one or both, strike the buffers T when the mechanism is carried forward and prevent excessive noise or jar of the parts, all as will readily be understood.

Having thus described my invention, what I 20 claim as new, and desire to secure by Letters Patent, is—

1. The combination, in an automatic fire-lighter, of a bed-plate or support, A, a rock-shaft, B, journaled thereto and carrying arms 25 C K, a bar, D, adapted to carry a match, a spring, S, adapted to draw the parts D E forward for lighting the match on a friction-surface, and a catch adapted to retain the trip-arm to hold the device set ready for action, 30 substantially as herein set forth.

2. The combination, in an automatic fire-lighter, of a bed-plate or support, A, a rock-shaft, B, journaled thereto and carrying arms C K, a bar, D, adapted to carry a match, a 35 spring, S, adapted to draw the parts D E forward for lighting the match on a friction-surface, and a catch-bar, L, adapted to retain the

parts K C D S, and fitted for withdrawal by a clock mechanism, substantially as described, for the purposes set forth. 40

3. The combination, in an automatic fire-lighter, of a bed-plate, A, a rock shaft, B, journaled thereto and carrying arms C K, a match-carrying bar, D, a spring, S, adapted to draw the parts D E forward for lighting the 45 match on a friction-surface, hooks H, for holding a kindling wad adapted to be lighted by the match, and a catch-bar, L, adapted to retain the parts K C D S, and fitted for withdrawal by a clock mechanism, substantially as 50 described, for the purposes set forth.

4. In an automatic fire-lighter, the match-holding bar or device formed with an eye, d, and provided with a pivoted hook, F, adapted to wedge the match in the eye, substantially 55 as herein set forth.

5. In an automatic fire-lighter, the combination, with a bed-plate, A, rock-shaft and arms B C, match-holding bar D, and a spring device drawing the parts B C D forward for 60 lighting the match, of buffers T, substantially as described, for the purposes set forth.

6. In an automatic fire-lighter, the combination, with the winding-mechanism shaft o of alarm-clock, of a cam disk or wheel, O, on 65 said shaft, a lever, N, pivoted to the frame, and a catch-bar, L, connected to said lever, substantially as described, for the purposes set forth.
